UNITED STATES PATENT OFFICE.

JOHN F. MONTGOMERY, OF TAUNTON, MASSACHUSETTS, ASSIGNOR OF ONE-HALF TO HENRY M. RYDER, OF SAME PLACE.

GRATE.

SPECIFICATION forming part of Letters Patent No. 253,880, dated February 21, 1882.

Application filed November 14, 1881. (Model.)

To all whom it may concern:

Be it known that I, JOHN F. MONTGOMERY, of Taunton, in the county of Bristol and State of Massachusetts, have invented a new and useful Improvement in Grates, of which the following is a specification.

My invention relates to grates in which a series of bars are connected to a device for shaking them; and the object of my improvement is to give a reciprocating motion to alternate bars, so that while part of the bars move in one direction the others will move in the opposite direction.

In the accompanying drawings, which illustrate a stove-grate embodying my invention, Figure 1 is a plan or top view of a grate with six bars, which are sufficient to illustrate my improvement. Fig. 2 is a bottom view of the same. Fig. 3 is a longitudinal section through the operating-bar, whose axis coincides with the axis of the dumping-frame, and which extends through one of the journals of the frame, made hollow for that purpose. Fig. 4 is a transverse section through the connecting arm or lever, which vibrates on a fulcrum and takes hold of downwardly-projecting pins on the operating-bar and on the bar next to it on line *xx*. Fig. 5 is a transverse section through one of the vibrating standards on line *yy*.

The frame *A* is provided with journals *a* and *a'*, on which it rests when in place, and on which it is turned for dumping, and consists of two end bars, *a²* *a³*, connected by longitudinal bars *a⁴*. These bars *a⁴* are joined at or near their middle by a connecting-bar, *a⁵*, provided with a pin, *a⁶*, forming a fulcrum, on which the connecting arm or lever *B* (hereinafter referred to) vibrates. Each of the bars *a⁴* of the frame *A* has two seats at each end, in which are seated four vibrating standards, *D*. These vibrating standards *D* are provided with a series of notches, *d*, in their upper edges, alternately shallow and deep, the shallow ones being formed to fit notches in alternate grate-bars, while the deep ones allow the other grate-bars to pass through them without contact.

The grate-bars *E* are placed parallel with each other and rest on the standards *D*, the notches in the alternate bars fitting on their

corresponding standards. One of the bars, *E'*, is placed with its axis coinciding with the axis of the frame and extends through the hollow journal *a'*, in which it is capable of being reciprocated. A feather, *e'*, works in a slot in the hollow journal and causes the frame to move with the bar *E'* when it is turned. The outer extremity of the bar *E'* is properly shaped to receive a suitable device for manipulating it. A downward-projecting pin, *e²*, is attached to the bar *E'*, and a similar pin to a bar next to it. These pins are inserted in openings in the arms of the connecting-lever *B*. Cap-pieces *a⁷* are placed over the ends of the grate-bars to guide them and to hold them in place, and are attached to the frame *A* by screws or bolts. One half of the hollow journal *a'* is cast on one of the cap-pieces, the other half being cast on the frame, and the journal *a* may be cast either on the other cap-piece or on the frame. These cap-pieces are perforated to increase the air-inlets.

In operation the bar *E'* is reciprocated and imparts motion to the alternate bars that are mounted on the same standards that it rests on, and through the connecting-lever *B* also imparts a reverse motion to the bar next to it, which communicates its motion to the bars resting on the same standards that it rests on, so that all the bars reciprocate in alternate opposite directions, thereby preventing cinders from becoming wedged in between the bars, and breaking up any clinkers that may be formed. By turning the bar *E'* the feather *e'* causes the other bars and the frame to turn with it, and the grate is thereby dumped.

I am aware of Patent No. 155,330, September 22, 1874, to C. A. Miller, which shows each bar supported at each end upon a pivoted arm. I am also aware that J. A. Moffitt in his Patent No. 190,236, May 1, 1877, shows alternate bars reciprocated in slides by connecting them in two sections to a longitudinally-divided shaft; and I am also aware that H. M. Ryder in his Patent No. 249,205, November 8, 1881, shows the bars connected together, so that the oscillation of one will cause the others to oscillate.

In my improved grate all the bars moving

in one direction are mounted on the same vibrating standards, so that only two pairs of these standards are required for any number of bars reciprocating alternately in opposite directions. Either grate-bar of one set can be connected to a grate-bar of the other set by a lever, so that motion in opposite directions may be communicated from one set to the other.

I claim as my invention—

5 to The improved grate herein described, having one set of bars moving in one direction mount-

ed on one pair of vibrating standards, the other set of bars mounted on a second pair of vibrating standards, a bar of one set being connected to a bar of the other set by a lever, so that by reciprocating one set the other set will reciprocate in the opposite direction, substantially as and for the purposes set forth.

JOHN F. MONTGOMERY.
